Claims priority, application Austria June 21, 1954

1 Claim. (Cl. 260—239.1)

The present invention relates to a process for preparing new salts of penicillin with organic bases which salts are difficultly soluble in water and are particularly suited for oral therapy.

It is known to prepare crystalline salts of penicillin G with organic bases, such as p-aminobenzoylethylaminooethanol-penicillin G or quinine-penicillin G which can either be used directly in therapy or which, like N-ethyl-piperidine-penicillin G or triethylamin-penicillin G constitute intermediate stages in the production of pure alkali or alkali earth salts of penicillin. The preparation of these relatively difficultly water-soluble base salts of penicillin can be effected in accordance with a known method of operation by reacting alkali or alkali earth salts of penicillin with base salts of organic or inorganic acids, for instance p-aminobenzoylethylaminooethanol hydrochloride, in aqueous or aqueous-alcoholic solution. In accordance with another method of operation which can be used also for the preparation of water-soluble base salts of penicillin, the free organic base is allowed to act in anhydrous organic solvents on the penicillin present in the form of free acid. Another known method which leads to base salts of penicillin which are only difficultly soluble or practically water-insoluble consists in reacting base salts of penicillin with certain base salts of organic or inorganic acids, the base of which differs from the base of the base salt of penicillin used; the base salts of penicillin obtained by this method are more difficultly soluble in the reaction medium than the base salts of penicillin used as starting material.

All previously known penicillins, penicillin salts or base salts of penicillin, due to the high sensitivity to acid of these penicillins, have the disadvantage of having a low stability so that there are great difficulties involved in their oral administration. An extensive decomposition of the antibiotic is effected by the free acid present in the stomach so that there were required up to the present time in general in order to obtain penicillin contents in the blood which definitely assure a therapeutic action, at least five to six times as much penicillin as had to be used in parenteral administration in order to obtain the same results. Furthermore, the penicillin salts could be taken only on an empty stomach. The use of various alkaline buffer additions in order to neutralize the hydrochloric acid of the stomach was it is true somewhat successful, but the production of an effective penicillin content in the blood still had inherent in it relatively large factors of uncertainty so that this form of application could not find introduction into general use. Later on, it was believed that the difficultly water-soluble base salts of penicillin G, for instance in p-aminobenzoylethylaminooethanol-penicillin G and in dibenzylethylene-diamine-penicillin G were better suited for oral therapy. Soon however one was forced to recognize also in this case that more favorable results were not obtained with the particularly difficultly water-soluble base salts of penicillin G than with the water-soluble penicillin salts. These difficultly soluble penicillin salts are also decomposed by the gastric acid

2

into the hydrochloride of the base and the free penicillin G acid, the latter being decomposed to the greatest extent due to its sensitivity to acid. It was only the introduction of the acid resistant penicillins which are used in the form of free acids which brought about an advance in this field. These acid-resistant penicillins, administered preferably in the form of tablets, show practically the same results as injection preparations, the quantity of penicillin used being only about 1½ times as great as the quantity of injection penicillin and furthermore administration on an empty stomach no longer being of such great importance.

The acid-resistant penicillins up to the present time could be administered only in solid form for instance as tablets or pills and it was not possible to use them in liquid form, for instance as an aqueous solution or suspension, such as in the form of the fruits syrups and the like which are so popular in pediatrics. An aqueous suspension of the acid-resistant penicillins (pH about 3) is stable only for a very short period of time; even at higher pH values (pH 5 to 7) at which the acid-resistant penicillins are already present in the form of water-soluble salts, the stability conditions are just as poor as in the case of solutions of penicillin G salts. Furthermore, it was found in the aqueous administration of solutions of the readily water-soluble alkali salts of acid-resistant penicillins that while higher concentrations in the blood can be obtained than when using the same dose of alkali penicillin G, the concentration in the blood is nevertheless below the values which are obtained upon the administration of the same quantity of free acids of the acid-resistant penicillins. The reason for this may well be that while the free-acid is liberated by the gastric acid also from the alkali salts of the acid-resistant penicillins, it remains for some time in supersaturated solution. In a supersaturated solution, the acid resistant penicillin acids are more stable than the free acid of penicillin G but less acid-resistant than the crystalline acid-resistant penicillin acids.

40 The object of the present invention is to prepare new difficultly soluble base salts of penicillins which do not experience a decrease in their activity either in neutral or in weakly acid or acid media and with which it is possible to prepare stable aqueous suspensions suitable particularly for oral therapy.

The method in accordance with the invention for the preparation of new difficultly water-soluble salts of penicillin with organic bases consists essentially in reacting acid-resistant penicillins with organic nitrogen bases such as acridine, diphenylethylamine, benzylphenylethylamine, dibenzylethylenediamine or the like, so as to form base penicillins which have a high stability in aqueous suspension and do not experience any substantial decrease of the penicillin activity in an acid medium. Furthermore, the bases dibenzylamine, phenylethylbenzylamine and the like can be reacted with the acid stable penicillins forming difficultly water soluble base penicillins.

By acid-resistant penicillins there is to be understood in the present invention, penicillins which have the general formula $C_8H_{10}O_3NS-NHCO-(R_1X)_n-R_2$ in which R_1 is a bivalent, possibly substituted, aliphatic radical, X is oxygen, sulfur or the NH group, n is a whole number from 1 to 5 and R_2 is an aliphatic, araliphatic and/or aromatic, possibly substituted, radical. These penicillins differ typically in their properties from the normal penicillins G, X, F and K. Examples of such acid-resistant penicillins are phenoxyethyl-penicillin, p-oxyphenoxyethyl-penicillin, p-nitrophenoxyethyl-penicillin, phenylmercaptomethyl-penicillin or the like.

In accordance with one particularly suitable embodiment of the invention, the new base salts of penicillin

can be prepared by reacting the free acids of the acid-resistant penicillins with the free organic bases in organic solvents such as butylacetate, amylacetate, ether, chloroform, acetone, etc. The acid-resistant penicillins can however also be reacted in the form of their salts, preferably their alkali or alkali earth salts, in aqueous solution, possibly with the addition of water-miscible organic solvents, for instance aliphatic amides such as formamide, acetamide and the like, with salts of organic bases. Furthermore, the difficultly soluble base salts of the acid-resistant penicillins in accordance with the present invention can be obtained in a good yield also by reacting the base salts of acid-resistant penicillins with base salts of organic or inorganic acids, possibly suspended in solvents, the bases of which are different from the bases of the base salts of the penicillin used and which form base salts which are more difficultly soluble in the reaction medium than the base salts of the penicillin which constituted the starting point. The said reactions can be carried out at normal or elevated temperature.

The solubility properties of the base salts of acid-resistant penicillins differ in many cases from the solubility properties of the corresponding base salts of penicillin G. Thus for instance the best known base salt of penicillin G namely p-aminobenzoylethylaminoethanol-penicillin G, at room temperature has a solubility in water of only about 0.5% while p-aminobenzoylethylaminoethanol-phenoxyethyl-penicillin at the same temperature has a much greater solubility, namely a solubility of about 6%.

It is known from the difficultly water-soluble penicillin G salts that the relatively more readily water-soluble salts such as novocain-penicillin G are not very stable in aqueous suspensions since the substantial fraction of the salt dissolved in the water decomposes, in which connection a further fraction of the solid phase passes into solution, etc. By reducing the solubility of the novocain-penicillin G which can be done for instance by additives having a common ion, such as novocain hydrochloride, there are obtained suspensions having a stability of about 1 year at room temperature. However, other particularly difficultly soluble penicillin G salts such as acridine-penicillin G, dibenzyl-ethylenediamine-penicillin G, etc. also give such stable aqueous penicillin suspensions.

These difficultly soluble penicillin G salts are decomposed in the stomach by the gastric acid forming the free penicillin G acid and the hydrochlorides of the base, in which connection, as a result of the acid instability of the free penicillin G acid a substantial loss in activity occurs so that these salts are practically just as unsuitable for oral therapy as the readily soluble alkali penicillin G salts.

In the case of the new base salts of the acid-resistant penicillins of the present invention, there does not occur upon passage through the stomach any loss in activity as noted even though to a far lesser extent than in the case of penicillin G salts, when using alkali and alkali earth salts of the acid-resistant penicillins. This is probably due to the fact that the solid phase of the base penicillin forms nuclei centers for the crystallization of the free acids of the acid-resistant penicillins, as a result of which supersaturation is responsible for the decrease in activity of the alkali and alkali earth salts of the acid-resistant penicillins in oral therapy is done away with. For the preparation of stable aqueous suspensions there are particularly well-suited base salts, the solubility of which in water is less than 0.2%, a base salt having a water solubility of between 0.03% and 0.1% being particularly advantageous.

Taking into consideration the fact that the milligram activities, due to the fact that the molecular weights generally do not differ very greatly, are about 800 to 1000 units, the saturated aqueous solutions have activities of an order of magnitude of about 1000 units per cc. 75

Base salts of acid-resistant penicillins, the solubility properties of which meet the above conditions are for instance acridine - phenoxyethyl - penicillin, dibenzylethylenediamine - phenoxyethyl - penicillin, phenylethylbenzylamine - phenoxyethyl - penicillin, diphenylethylamine-phenoxyethyl-penicillin and the like. In the oral administration of such stable suspensions of difficultly water-soluble base salts of acid resistnt penicillins, there takes place, under the action of the gastric juice a conversion into the hydrochloride of the base and of the free acid-resistant penicillin acid. As a result of the acid resistance of the free acids of these penicillins, the same blood concentrations are obtained as with the said penicillin acids if approximately the same doses are used as customary in the administration of acid-resistant penicillin acids.

The dibenzylethylenediamine-phenoxyethyl-penicillin prepared in accordance with the present invention has a not unsubstantially greater water solubility than the corresponding salt of penicillin G (0.03% as compared with 0.01% at room temperature), which results in certain advantages in connection with the parenteral use of this compound. Thus it was possible with dibenzylethylenediamine-penicillin G after a single injection still to detect penicillin in the blood after many days and in some cases even after 1 to 2 weeks. Long-lasting penicillin concentrations in the blood are to be sure desirable but on the other hand, such concentrations can also entail substantial risks. Thus, for instance, in certain cases, the resistance of pathogenic germs can be favored thereby. Corresponding to the very low water-solubility of dibenzylethylenediamine-penicillin G, the blood concentrations even after only 1 to 2 days have such an order of magnitude that this danger of the production of resistance to pathogenic germs exists. Upon viewing the blood concentration curves obtained in the therapeutic administration of this penicillin G salt, it is seen that starting from the 2nd or 3rd day after the injection, the concentration in the blood is in the region of about 0.06 to 0.12 Oxford units per cc. of serum and that this value under certain circumstances remains at this level for many days. In view of the fact that by the formation of resistant strains, the sensitivity limits in the case of many pathogenic staphylococci and streptococci have been substantially increased, in many countries today a value of 0.1 Oxford units per cc. of serum is taken as the lowest limit for a therapeutically active penicillin concentration in the blood. Blood concentrations which lie below the said value or do not substantially exceed it are the more dangerous the longer they appear in the blood plasma. Aside from the dangers inherent in the use of such difficultly soluble penicillin salts in therapy, allergy phenomena which in certain cases appear also after treatment with other penicillin salts, may lead to severe complications. A patient treated for instance with dibenzyl-ethylenediamine-penicillin G is under the effect for a long time of the compound which possibly has the action of an allergen, and cannot be freed from the allergic effects.

Dibenzylethylenediamine-phenoxyethyl-penicillin after an injection of for instance 300,000 units also gives it is true blood concentrations which still amount after two to three days to about 0.1 unit per cc. However, these values rapidly drop as the result of the greater water solubility of this penicillin salt, so that long continuing blood concentrations in the region of 0.06 to 0.12 unit per cc. are avoided.

Dibenzylethylenediamine-phenoxyethyl-penicillin also appears to be a salt which has optimum solubility for depot preparations which are to be administered parenterally, since its solubility is between the solubility of p-aminobenzoylethylaminoethanol-penicillin G and dibenzylethylenediamine-penicillin G.

Example 1.—To a solution of 7.44 grams phenoxyethyl-penicillin sodium of 1600 units per milligram in 200 cc. of water there were added 3.2 grams dibenzyl-

ethylenediamine hydrochloride which had been dissolved in 200 cc. of water. There was immediately formed a precipitate of dibenzylethylenediamine-phenoxyethylpenicillin which was suction filtered, washed with water and dried. Yield: 9.1 grams dibenzylethylenediamine-phenoxyethylpenicillin of 1160 units per milligram (iodometric test)=87.7% of the theoretical amount.

The substance upon being dried to constant weight had a melting point of 105 to 109° C.; solubility in water was 0.03% at 24° C.

Example 2.—To 200 cc. phenoxymethyl-penicillin-containing butylacetate phase at 59,500 units per cc. (iodometric test) there were added 4.22 grams phenylethylbenzylamine base which had been dissolved in 200 cc. butyl acetate. The precipitate of phenylethylbenzylamine-phenoxyethyl-penicillin which formed after standing for several hours was suction filtered and thereupon washed with ether and finally dried. The yield was 10.6 grams phenylethylbenzylamine-phenoxyethylpenicillin at 1016 units per milligram (iodometric test)=90.5% of the theoretical amount. The solubility in water was 0.09% at 24° C.

Example 3.—1.35 grams quinine-phenoxyethyl-penicillin at 802 units per mg. were suspended in a solution of 0.67 gram 2-ethoxy-6,9-diaminoacridin-lactate (Rivanol) in 30 cc. of water. The suspension was shaken for three hours in a shaking machine at room temperature and thereupon set aside for about 12 hours at a tem-

perature of 4° C. In this way there were obtained 1.12 grams 2-ethoxy-6,9-diaminoacridin-phenoxyethyl-penicillin at 860 units per mg. (iodometric test) which corresponds to a yield of 89.2% of the theoretical amount. The solubility in water was 0.11% at 24° C.

We claim:

As a new compound, the phenoxy-methyl penicillin salt of N,N'-dibenzylethylenediamine.
